UNITED STATES PATENT OFFICE.

AUGUST BURGERT, OF MÜLHAUSEN, GERMANY, ASSIGNOR TO ELSAESSISCHE MASCHIN-
ENBAU GESELLSCHAFT, OF MÜLHAUSEN, GERMANY, AND EDUARD MERTENS, OF
FREIBURG, BREISGAU, GERMANY.

ADJUSTABLE BEARING FOR PRINTING-MACHINE ROLLERS.

1,068,562.

Specification of Letters Patent.

Patented July 29, 1913.

Application filed May 31, 1913. Serial No. 771,047.

To all whom it may concern:

Be it known that I, AUGUST BURGERT, chief engineer, a subject of the Emperor of Germany, residing at 2 Synagogenstrasse, 5 Mülhausen Elsass, Germany, have invented a new and useful Improved Adjustable Bearing for Printing-Machine Rollers, of which the following is a specification.

In the operation of printing upon end-
less paper or fabric, especially in rotatory
intaglio printing, with the application of
elastic intermediate rollers, great difficulties
are liable to occur when the pressure upon the
two ends of the printing or the pressure cylin-
der respectively are not adjusted exactly to
correspond, or when the elastic cover of the
pressure cylinder does not press uniformly,
or when the printing machine itself is not
sufficiently fixed. In any of these cases, the
paper or material is liable to form folds or
20 to tear and the printing surface and the
elastic pressure cylinder are liable to be
damaged.

The object of the present invention is a
25 double acting pressure regulating device
which is devised to obviate the above men-
tioned drawbacks.

The drawing illustrates the invention as
follows:—

30 Figure 1 shows a plan view of the appa-
ratus. Fig. 2 is a section of Fig. 1 on the
line X—Y of the printing machine as de-
scribed in which the inking mechanism has
been omitted because it does not form any
35 part of the present invention.

In these drawings A indicates a shaft
which is rotated by means of the wheel F.
Upon the shaft A are secured the two cone
wheels B and D. By the rotation of B
40 and D, the wheels C and E are revolved
upon their axles together with the screws
G and H attached to them and by the turn-
ing of the latter, the journals Q and R of
the pressure cylinder J are drawn nearer
45 to the printing cylinder K or removed far-
ther from them. The approach or the re-
moval of Q and R takes place quite uni-
formly, if the printing machine and all its
parts are mounted in the most exact man-

ner and are in good condition. If this, how-
ever, is not the case, then the approach of
Q and R being effected indirectly by turn-
ing the wheel F, will not be uniform. In
order, notwithstanding this, to obtain a uni-
formity of this approach the cone wheel B 55
is not keyed fast upon the shaft A but is
placed loose upon it, and is so connected
by means of the worm L with the fixed worm
wheel N on the shaft A that it can easily be
turned by means of the key M upon the 60
shaft A with regard to the wheel D. By
this adjustment of the wheel B the pres-
sure for the bearing R can easily be ad-
justed independently of that for the bear-
ing Q. 65

What I claim is:

1. In a rotary printing machine, duplex
adjusting mechanism for the journals of the
impression cylinder, comprising an adjust-
ing shaft, a handwheel on said shaft, cone
70 wheels on said shaft, a pair of screw
spindles supported in the machine frame,
each revolubly secured at one end to one
bearing of the impression cylinder, a bevel
wheel on the end of each screw spindle 75
adapted to engage with the respective cone
wheel; in combination with a worm gear
rigidly attached to one cone wheel, and a
worm wheel keyed on said adjusting shaft
said mechanism so arranged that the said 80
cone wheel while participating in the rota-
tion of the adjusting shaft, can be inde-
pendently rotated around said shaft by turn-
ing the worm gear; for the purpose of ad-
justing the one axle bearing independently 85
of the other.

2. In a rotary printing machine, mecha-
nism for combined and independent adjust-
ment of the impression cylinder, journals
Q, R comprising the handwheel F keyed on
the shaft, the cone wheel D keyed on said
shaft, the bevel wheel E meshing with said
cone wheel, the spindle H secured to the
journal Q and supported in the machine
frame; in combination with the cone wheel 90
B loose on the shaft A, the worm L fixed to
the cone wheel B, the worm wheel N keyed
on the shaft A and meshing with the worm 95

L, the bevel wheel C adapted to engage with the wheel B, the screw spindle G secured at one end to the wheel C and at the other end to the journal R; said worm L being
5 adapted to be turned by the screw key M for the purpose of altering the position of the journal R relatively to the journal Q.

In testimony whereof I have signed my name to the specification in the presence of two subscribing witnesses.

AUGUST BURGERT.
